UNITED STATES PATENT OFFICE.

THOMAS EDWARD MURRAY, JR., OF BROOKLYN, NEW YORK, ASSIGNOR TO THOMAS E. MURRAY, OF NEW YORK, N. Y.

ELECTRIC FUSE.

1,120,226.

Specification of Letters Patent.

Patented Dec. 8, 1914.

Application filed March 28, 1914. Serial No. 827,362.

To all whom it may concern:

Be it known that I, THOMAS E. MURRAY, Jr., a citizen of the United States, residing at Brooklyn, in the county of Kings and 5 State of New York, have invented a certain new and useful Improvement in Electric Fuses, of which the following is a specification.

The invention relates to electric fuses. It 10 is based on the discovery of and embodies a new principle, namely, that if in a fuse strip a blowing point be localized, and the said blowing point be inclosed in a solid body of insulating material, which forms 15 with said strip a gas-tight joint on both sides of said blowing point, then the destruction of the strip upon explosion will extend no farther than said joints, or, in other words, will be confined within said insulating body, and the gas generated in the 20 confined space within said body will blow the ruptured ends of said strip out of said space, as from a gun, thus widely separating said ends and even curling or bending 25 them back on themselves.

In the accompanying drawings—Figure 1 is a longitudinal section of my fuse. Fig. 2 is a transverse section on line x, x of Fig. 1. Fig. 3 shows a fuse strip separately. Fig. 4 is an enlarged cross section of the middle portion of the partition of insulating material, showing the localized blowing point of the strip in the slot of said partition. Fig. 5 is a face view of the same portion of the 35 partition, showing said strip in cross section. Figs. 6 and 7 are sectional views similar to Fig. 1. Fig. 6 shows the fuse at the instant of blowing, and exhibits the ruptured portion of the fuse strip as confined 40 in the slot in the partition, the view being taken at right angles to Fig. 1. Fig. 7 shows the fuse strip after the ruptured ends have been expelled from the partition slot by the gas formed therein, and exhibits the 45 throwing back and curling up of the parts of the fuse, as hereinafter described.

Similar letters of reference indicate like parts.

My invention may be embodied in many 50 different constructions. I herein illustrate its application to the simple and well known "cartridge" fuse, which comprises a cylindrical shell A of fiber or other suitable insulating material, metal caps B on the ends of 55 said cylinder, a fuse strip C within the shell

and connected at its ends to said caps, and sometimes asbestos lining disks D covering the inner faces of the caps.

I provide within the shell and closely fitting the same, a partition disk E of insulating material. In that disk I make a slot F . I make the fuse strip C preferably in the form of a flat band. I localize the blowing point at H in that strip by reducing its cross sectional area at said point by means 60 of indentations or recesses in opposite edges of the strip.

The localized blowing point H is to lie in the slot F , and the insulating body E is to form a gas-tight joint with the strip on 65 both sides of and in proximity to said blowing point. Where the blowing point is formed, as here shown, by a contraction in the strip, the insulating body E is to form a gas-tight joint with the strip on both sides 70 of said contraction. In other words, the strip is to completely close or plug both ends of the slot, as indicated at J , Fig. 4, and the localized blowing point, however produced, is to lie in that part of the strip 75 which is within the slot and between said closed or plugged ends. To this end in the embodiment here shown, the width a, b , Fig. 4, of the recesses in the edge of the strip is made less than the thickness of body 80 E . When these conditions are fulfilled, I find by actual and repeated tests that the following results ensue: (1) The portion of the strip which is destroyed is limited to so much of the strip as lies in the partition 85 slot, as indicated in Fig. 5, so that the destruction or rupture does not extend to the parts of the strip outside of said partition.

(2) By reason of the confinement of the 90 gases of explosion to the partition slot, said 95 gases act to throw the ruptured ends of the strip immediately out of the slot, and to force them asunder, so that the gap between them then becomes so great that there can be no passage of current between them, and 100 this passage is still further prevented by the barrier due to the presence of the insulating partition. In practice, I have repeatedly observed that the ends of the strip 105 are not only widely separated, but curled or bent back on themselves, as shown in Fig. 7.

The advantages will be obvious to all skilled in the art, since the conditions of practically a perfect fuse are here realized. No filling of plaster or the like within the 110

fuse case is either necessary or desirable. The whole explosion is limited to the very small confined space afforded by the partition slot, and the correspondingly small 5 amount of gas generated does not rupture the shell. The strip beyond the partition not being consumed, the effects of explosion do not extend to the end caps and terminal connections.

10 I do not limit myself to the particular way of producing a localized blowing point in a strip of fusible material shown in Fig. 3, since there are many known ways. The body of insulating material may or may not 15 form a partition in the shell or form a barrier between the fuse terminals. The fuse strip may be of cross section other than polygonal.

I claim:

20 1. An electric fuse, comprising a fuse strip having a localized blowing point, and a body of solid insulating material inclosing said blowing point and forming a gas-tight joint with said strip on both sides of and 25 in proximity to said blowing point; the width of said joint being such that upon the rupture of the fuse at said localized blowing point, the separated unmelted parts of said fuse immediately adjacent to said point of rupture 30 shall be expelled from said body.

2. An electric fuse, comprising a fuse strip having a contraction forming a localized blowing point, and a body of solid insulating material inclosing said contraction and forming a gas tight joint with said strip on both sides of and in proximity to 35 said contraction; the width of said joint being such that upon the rupture of the fuse at said localized blowing point, the separated unmelted parts of said fuse immediately adjacent to said point of rupture shall be expelled from said body.

3. An electric fuse, comprising a shell, a fuse strip therein having a localized blowing point, a partition of solid insulating material in said shell inclosing said blowing point and forming a gas-tight joint with said strip on both sides of and in proximity to said blowing point; the width of said joint being such that upon the rupture of 45 the fuse at said localized blowing point, the separated unmelted parts of said fuse immediately adjacent to said point of rupture shall be expelled from said partition.

In testimony whereof I have affixed my 55 signature in presence of two witnesses.

THOMAS EDWARD MURRAY, JR.
